UNITED STATES PATENT OFFICE.

SAMUEL S. AMDURSKY, OF ROCHESTER, NEW YORK, ASSIGNOR TO TAYLOR INSTRUMENT COMPANIES, OF ROCHESTER, NEW YORK, A CORPORATION OF NEW YORK.

HYGROMETRIC APPARATUS.

Application filed January 7, 1926. Serial No. 79,909.

This invention relates to hygrometric apparatus and, more particularly, to the variety employing a sensitive, thermometric element or bulb arranged in a current of air saturated by a water spraying device or other suitable means for affording the desired wet bulb temperature. One object of the invention is to provide an improved and more efficient apparatus of the character described embodying a construction and arrangements of parts adapted to dispose of dust, lint and other impurities in the current of air and thus particularly suitable for use in paper and other mills and factories where the air is laden with such impurities. Another object is to provide such an apparatus comprising an efficient arrangement of parts for eliminating impurities from the air current before the latter reaches the saturating or spraying device. A further object is to provide an apparatus of this character embodying an efficient arrangement for intermittently flushing the spraying chamber for the purpose of washing out any impurities and dirt collected therein. A further object is to provide such apparatus having a device for spraying the air current with water and intermittently threading the orifice of said device to clear the same of accumulated dirt and at the same time flushing the said orifice and the walls of the spray chamber with water to clean the same. Still a further object is to provide an apparatus of the character described having its parts combined with an instrument board in a convenient and practical manner.

To these and other ends the invention resides in certain improvements and combinations of parts, all as will be hereinafter more fully described, the novel features being pointed out in the claims at the end of the specification.

In the drawings:

Figure 1 is a central vertical sectional view of a hygrometric apparatus embodying the present invention;

Figure 2 is a reduced detail elevation of parts shown in Figure 1, as seen from line 2^a—2^a;

Figure 3 is an enlarged sectional view of a portion of the water supply system shown in Figure 1;

Figure 4 is an enlarged sectional view of

the saturating device or spray head shown in Figure 1;

Figure 5 is an enlarged sectional view substantially on the line 5^a—5^a in Figure 1; and

Figure 6 is an enlarged sectional view of a chamber flushing nozzle substantially on the line 5^a—5^a in Figure 1.

Similar reference numerals throughout the several views indicate the same parts.

The present invention is shown herein, by way of illustration, as embodied in an apparatus adapted for mounting on an instrument board 10, the front of which is viewed from the left in Figure 1. The apparatus comprises a main or spray chamber 11 in which the current of air is saturated with water and in which the thermometric element or wet bulb is located. The chamber 11 is constructed, in the present instance, of a casting 12 having the general form of an elbow, one leg of which 13 is secured and sealed in any suitable manner to the instrument board in registry with an opening 14 in the latter for the passage of air into the spray chamber. The other leg 15 of the latter has fitted thereto the upper end of a cylindrical or tubular sleeve portion 16 conveniently constructed of transparent glass to afford opportunity for inspection of the interior of the apparatus. The other or lower end of sleeve portion 16 is fitted to a supporting sleeve 17 mounted in any suitable manner as by means of a bracket 18 on the instrument board. The other end of sleeve 17 has fitted thereto a discharge pipe 19 preferably turned rearwardly and passing through an opening in the instrument board to a suitable disposal point in rear of the latter. Means are provided, as hereafter described, for directing a spray of water into the current of air at the upper end of sleeve 16 in which latter, at a point lower down, the wet bulb is positioned.

The current of air to be measured is preferably supplied to the spray chamber through the instrument board opening 14 through a conducting member 20 mounted on the rear of the instrument board. This member may be described in a general way as having an outline shape resembling that of an artillery shell. That is to say, it has a main cylindrical portion 21, the walls of

which are curved and contracted as at 22 at its lower end where the member is provided with a discharge opening 23. The cylindrical portion of the member has a lateral conduit 24 communicating therewith and mounted and sealed at its other end in any suitable manner against the rear wall of the instrument board around the opening 14. Within the cylindrical portion 21 of the member are transversely and downwardly directed baffle plates 25 and 26 which tend to throw dust, lint and other solid particles toward the bottom of the member and discharge the same through opening 23, the purified air current passing between baffles 25 and 26 and through opening 14 and into the top of the spray chamber 11. The saturating device or spray head is indicated, generally, at 27 as mounted in the upper end of a flange 28 extending upwardly from the top of the elbow 11 of the spray chamber. This spray head is shown in detail in Figure 4 as comprising a hollow casing 29 having a pipe connection 30 communicating with its interior. The casing is formed at its bottom with a circular orifice 31 into which extends the reduced lower end of a nipple 32 having at the said lower end a reduced orifice 33. Nipple 32 has a pipe connection 34 communicating with its bore and sliding longitudinally in the latter is a plunger 35 guided in a casing or housing 36 containing a compression spring 37 which normally holds the plunger raised as shown. The lower end of the plunger carries a needle 38 adapted, when the plunger is depressed, to thread the orifice 33 and so clear the same of any collection of dirt which might otherwise tend to clog it. Water under suitable pressure is supplied through connection 34 to orifice 33 and compressed air is supplied to connection 30. It will be noted that orifice 31 is larger than the outside diameter of the orifice end of nipple 32, so that the air escapes through an annular ring about the water orifice and there is thus formed an atomizing or spraying head adapted to direct an effective cone-shaped spray or air and water downwardly into the spray chamber or, in other words, into the upper end of sleeve 16. Plunger 35 may be intermittently depressed by hand or by any suitable motor, being shown in the present instance as equipped with a solenoid device for intermittently actuating the same as hereafter more particularly described.

The means for flushing the spraying head orifice and the spray chamber to clear the same of collected impurities is preferably in the form of a compound nozzle 39 projecting tangentially through the depending leg 15 of the elbow 11 as shown and having a connection 40 for the supply of water under pressure thereto. This nozzle has an upwardly directed orifice 41, Figure 6, arranged to direct a jet of water with consid-

erable force against the lower end of the spray head and the nozzle orifice of the same to wash off any dirt collected thereon and, particularly, such as may be forced therethrough by the depression of the clearing needle 38. Nozzle 39 has an additional orifice 42 adapted to direct a jet of water circumferentially against the cylindrical walls of the spray chamber so that the latter is flushed with a current or film of water and thoroughly washed. The water supply connection 40 for nozzle 39 is preferably controlled by any suitable form of valve indicated generally at 43 and supplied with water under suitable pressure through a pipe 44. Valve 43, in the present instance, has a plunger 45 adapted to be depressed to open the valve by a lever 46 pivoted at 47 on the valve casing. It is apparent from this description that movement of lever 46 toward the valve depresses spindle 45 to open the valve, the latter having any suitable form of construction for the purpose.

Means are preferably provided for simultaneously depressing plunger 35 to thread and clear the spray head orifice and to flush the latter and the interior of the spray chamber through nozzle 39, comprising, in the present instance, an inclined end 48 on valve lever 46 lying in the path of downward movement of a cone shaped portion 49 on the lower end of a rod 50 carrying the armature of the solenoid 51 suitably fixed on the instrument board. Armature portion 49 is disposed, as shown, above the end of plunger 35 so that, when the solenoid is operated to produce a downward movement of armature portion 49, plunger 35 is depressed and valve 43 fully opened for the purposes described.

Means are preferably provided, also, for maintaining a small flow of water through the discharge pipe 19 of the spray chamber for washing away accumulated dirt, as shown, by the pipe 52 provided at the front of the instrument board with a sight feed 53 for observing the rate of flow. Pipe 52 is continued upwardly in rear of the instrument board and into an overflow device or container 53^a supplied with water through a pipe connection 54. The latter is controlled by valve 55 to throttle down the flow to a desired volume. Pipe 52 is extended upwardly in container 53^a as shown at 56 to form an overflow connection, and container 53^a is connected adjacent its bottom by a pipe 57 with connection 34 of the spray head. It is apparent from this arrangement that the flow of water to the spray head may be throttled down by the valve 55 until a suitable overflow stream is provided through pipe 52 for flushing the spray chamber discharge pipe 19.

The thermometric element or elements, of which one or more may be provided, are located in the lower portion of the spray

chamber as shown in Figures 1 and 2. To this end the supporting sleeve 17 is provided externally with bosses 58 through openings in which the thermometer capillaries 59 are inserted to locate the bulbs 60 at their ends in the spray chamber, as shown, in position to effectively encounter the saturated current of air. At 61, Figure 1, is shown a dry bulb element similarly inserted in the inlet member 21 in advance of the spray head to afford, if desired, a dry bulb measurement of the temperature of the air current.

The operation of the apparatus is apparent from the above description of its construction. With water and air under pressure supplied to the spray head, the current of air circulated in any suitable manner through the spray chamber is effectively sprayed and saturated before the current encounters the wet bulb elements 60, so that the latter afford the desired wet bulb measurements. The dirt, lint and other impurities in the air are largely removed by the baffle construction of the member 20 but such remaining quantity of foreign matter as may adhere to the walls of the spray chamber is effectively removed by the flushing action of nozzle 39. The spray head orifice is cleared by depression of plunger 35 at the same time that nozzle 39 is operated to flush the chamber, by the intermittent operation of solenoid 51 although it will be understood, of course, that these parts may be operated by hand or by another form of motor and a small flow of water through discharge pipe 19 is maintained by the overflow through pipe 52.

The invention thus provides a simple, practical and efficient form of apparatus particularly advantageous for installation in paper and similar mills and factories where the operation of the common form of hygrometric apparatus would be interfered with or prevented by the presence, in large quantities, of dirt, dust, lint and other foreign matter in the air which tends to quickly clog up and

interrupt the operation of such apparatus without suitable precautions for taking care of the same. The invention likewise provides a convenient, compact and self-contained unit adapted to be installed upon an instrument board with the inlet and discharge portions on the rear of the latter so that the whole presents a pleasing appearance.

I claim as my invention:

1. In a hygrometric device of the character described, the combination with a spray chamber, a spray device therein, a thermometric element subjected to the action of the spray, an outlet and an air inlet, of means automatically operative to remove from the spray device impurities deposited thereon including means for directing a jet of liquid against the spray device.

2. In a hygrometric device of the character described, the combination with a spray chamber, a spray device therein, a thermometric element subjected to the action of the spray, an outlet and an air inlet for the spray chamber, of means automatically operative to remove from the spray device impurities deposited thereon, and means in advance of the air inlet for removing from the air impurities suspended therein.

3. Apparatus according to claim 1, including means automatically operative to remove impurities deposited on the said outlet.

4. In a hygrometric device of the character described, the combination with a spray chamber, a spray nozzle for producing a spray therein, a thermometric element subjected to the action of the spray nozzle and means automatically operative to remove from the spray nozzle impurities deposited therein, including a needle for movement through the spray nozzle, means for directing a jet of liquid against the nozzle and means for concurrently operating the needle and the jet.

SAMUEL S. AMDURSKY.
